BASE FOR TABLE LAMPS

Edwin I. Cole, Eagle, Wis., assignor to The Stiffel Company, Chicago, Ill., a corporation of Illinois

Filed Nov. 16, 1959, Ser. No. 58,355

Term of patent 7 years

(Cl. D48—20)

The figure is a perspective view of a base for table lamps, showing my new design. The sides of the base not shown are the same in appearance as the side shown.

The dominant features of my design are shown in solid lines.

I claim:

The ornamental design for a base for table lamps, as shown and described.
